UNITED STATES PATENT OFFICE.

ALPHEUS E. HOLCOMB AND LESLIE A. RUSSELL, OF MILWAUKEE, WISCONSIN, AS
SIGNORS TO KOEHRING COMPANY, OF MILWAUKEE, WISCONSIN, A CORPORATION.

CONVERTIBLE CRANE.

Application filed August 11, 1922. Serial No. 581,200.

To all whom it may concern:

Be it known that we, ALPHEUS E. HOLCOMB and LESLIE A. RUSSELL, citizens of the United States, residing at Milwaukee, in the county of Milwaukee and State of Wisconsin, have invented certain new and useful Improvements in Convertible Cranes, of which the following is a specification.

Cranes of the locomotive or portable type as commonly in use today may be divided into three main classes, viz, those for clam-shell work which are especially designed for operating equipment comprising a clam-shell bucket; drag-line excavating cranes, the buckets of which operate on the drag principle; and shovel type cranes which employ a dipper arm and bucket equipment, and are commonly known as power or steam shovels. The operating machinery of cranes of the above types is carried primarily in a car or body mounted on a suitable portable truck which may take a number of different forms dependent upon the particular character of work for which the machine is especially to be used. As a general thing today, the machinery of each kind of crane hereinbefore referred to, by which the particular type of bucket equipment is operated, is designed for the actuation of its special bucket equipment, and no other. In order to convert one kind of crane such as that for clam-shell bucket work into another kind of those noted, it has been proposed to remove and replace certain of the drum mechanism in the car or body of the crane and by so doing, with the change of the cable and bucket equipment itself, the crane may be used to do other kinds of work. The clam-shell bucket operating crane may in this way be changed into a drag-line bucket crane. However, the removal of one part of the machinery in the car or body of the crane and its replacement involve time taking operations of considerable expense, and the laying up of the machine temporarily for the purpose, with consequent loss incident to so doing.

The principal aim of the present invention has been to so design the general operating machinery of a crane for general excavating work, that said machinery will be capable of operating different types of bucket equipment without requiring modification of the design of the machinery itself. In other words, our crane is convertible from

one capable of doing clam-shell work into one doing drag-line work, by the simple substitution of the required types of buckets and proper training of cables into connection with the specially designed operating instrumentalities of the machinery on the car or body of the machine. Said machinery as regards its various cable drums and driving means is not required to be changed by way of alteration or substitution of different parts, in any way. Likewise, by the placing into position of a suitable boom, a dipper handle and shovel, in lieu of the boom used for clam-shell, drag-line, and other work, and the connection of the cables in a proper manner with the controlling drums of the car or body, our crane may be converted into a power shovel.

By the reference to "other work," above mentioned, we have in mind that the crane employed by us is of such a construction as regards the boom equipment, that the clam shell type may be readily converted into a crane for general hoisting work, as well as for pile driving and other kinds of work, owing to certain change speed provisions for the operating drums, as presented in the co-pending application of Alpheus E. Holcomb, filed February 2, 1922, Serial No. 533,633.

In so far as we are aware, our crane is the first one ever developed which is capable of conversion to perform clam-shell, drag-line, and dipper shovel work, without drum removals and replacements or other material modification of the machinery in the car body of the crane; nor are we advised that it has ever been proposed or accomplished heretofore, to devise a crane which will without substantial change of the operating machinery be adapted for doing clam-shell, drag-line, power shovel, general hoisting at various driving speeds, and pile driving work, with the most efficient speed known for doing each particular class of work.

It is, therefore, desired that the scope of our invention as herein presented, be determined in the light of the foregoing outline of purpose and attainment, and that our claims finally appended hereto be read with said outline of invention in view.

In the accompanying drawings:

Figures 1, 2, and 3 are general diagrammatic side views showing clam-shell, drag-line, and power shovel cranes respectively. As regards the general features of the bucket

105

110

2
or shovel equipment they are largely conventional, but are employed in conjunction with the specially designed controlling machinery admitting of the convertibility 5 phases of action hereinbefore presented.

Figure 4 is a fragmentary side view somewhat similar to the previous views but illustrating general hoisting tackle equipment that may be used in conjunction with the 10 crane of our invention.

Figure 5 is a plan view showing in a general way the operating machinery of the crane which is carried in the car or body thereof.

15 Figure 6 is a fragmentary view bringing out more fully the driving connections intermediate the main operating drum of the machine and the dipper stick or arm for crowding out or projecting the shovel dipper 20 and for retracting or racking in the same in the customary operation of shovel type cranes.

Figure 7 is a sectional view taken about on the line 7—7 of Figure 6.

25 Figure 8 is a sectional view taken about on the line 8—8 of Figure 7.

Figure 9 is a fragmentary view of the main operating drum shaft and its operating drum equipment and controlling devices 30 with certain parts broken away to show more clearly what they look like in section, and said parts also illustrated partially in elevation.

Figure 9^a is a section taken about on the 35 line 9—9 of Figure 9 and bringing out more clearly the planetary gearing employed.

Figure 10 is a view of a modified form of an operating drum with a sprocket driving element applied thereto.

40 Figure 11 is a sectional view taken about on the line 11—11 of Figure 10, showing a modified drive means for the shipper shaft.

Figure 12 is a sectional view of the modified form of auxiliary reversing drum on 45 the boom.

Figure 13 is a view similar to Fig. 9, but showing still another modified type of operating drum in which a tag-line drum is utilized as a crowding drum and the main 50 operating drum employed for the racking in function, respecting the dipper stick of the shovel type machine.

Figure 14 is a view of the planetary gearing and friction clutch mechanism illustrated on a section taken thru the construction as shown in Fig. 13.

55 Figure 15 is a detail view of certain cable tension means that may be used for the crowding and racking in cable.

60 Figure 16 is a sectional view showing more clearly the cable tension means of Fig. 15.

65 A general understanding of the main operating machinery of the crane, which is of special design involving largely many

of the features embodied in the application previously identified, must be had to comprehend the manner in which the convertibility effects of the invention may be obtained. Referring to Figure 5 thereof, A 70 denotes the car or body of the machine that is adapted to turn in the usual way by means of the turn-table gear 1 and the turning pinion 2, seen best in Figures 1 to 3 inclusive, the same being operated reversibly in any suitable and conventional manner thru suitable driving connections with an engine 3 mounted in the body A. The operating machinery includes certain drums which for the convenience of this 80 description will be called the main operating drum 4 and the main hoisting drum 5, the former located in front of the latter and at a lower elevation. I utilize change speed drive gearing intermediate the engine shaft 85 6 and the drums 4 and 5. This gearing may be briefly described as comprising the drive pinion 7 engaging the transmitting gear 8 which in turn engages the drive gear 9 co-operating with a high speed drive gear 10 90 located adjacent to one end of a jack-shaft 11. A clutch conventionally illustrated at 12 is adapted to operatively connect the gear 9 to the shaft 11. From the shaft 11 power may be transmitted for driving the 95 pinion 2 enabling turning of the body A of the turntable, and swinging of its boom, in the well known manner. Also from the shaft 24 may be operated a hoisting drum (not shown) connected by a cable 13 with the peak of the boom 14, for peaking the 100 point of the boom in and out in the well known way. The gear 10 meshes with the high speed driven gear 15 on the counter-shaft 16 and the clutch 17 is adapted to connect the gear 15 with said counter-shaft 16. The shaft 11 carries on its right hand end opposite that having the gear 10, a slow speed driving gear 18 adapted to be connected to rotate with the shaft 11 by means 105 of a clutch 19. A slow speed driven gear 20 meshes with the gear 18 and may be connected with the shaft 16 by a clutch 21. The right hand portion of the shaft 16 is connected by a high and low speed gear 22 and a gear 23 with the shaft 24 on which the hoisting drum 5 is mounted. This shaft 24 is geared to the main operating shaft 25 which carries the main operating drum 4 by means of the gears 26 and 27 keyed 110 to the shafts 24 and 25 respectively. The high speed drive is secured by clutch 12 being active, and a drive through gear 9, shaft 11, gear 10, gear 15, shaft 16 (clutch 17 active), gears 22, 23, and shaft 24. Low speed of drum drive is obtained through gear 9, shaft 11, gear 18, gear 20, gears 22 and shaft 24, (clutches 19 and 21 active, and clutch 17 thrown out). To operatively connect the shaft 24 with the main hoist drum 115

5, a friction clutch 28 is employed, and for a like purpose, to connect the shaft 25 with the main operating drum 4, a similar friction clutch 29 is utilized. The cable which 5 winds about the drum 5 is customarily a hoisting cable in its function irrespective of whatever the type of crane into which our machine is converted, may be. The cable which winds about the drum 4, however, 10 performs a hoisting function largely when the machine is handling clam-shell bucket equipment; said cable, however, becomes a drag cable when the machine is doing drag-line bucket work, under which conditions 15 the drum 4 is a drag drum; and in regard to shovel work the cable winding about the drum 4 is operated with reverse driving connections thereon, under which conditions such cable and drum constitute combined 20 crowding and racking in means for the dipper stick or arm of the shovel.

The gearing which we have described in a general way, for driving the drums 4 and 5, may be of different kinds, the effort herein 25 being merely to set forth some conventional gearing enabling the transmission of different speeds from the engine 3 to the drums 4 and 5, high speed obtainable by using the high speed drive off the gear 10, and low 30 speed used when the slow speed drive off the gear 18 is employed. Any conventional means are utilized for operating the clutches or shifting the gears to obtain the change in speed ratios for the operation of the said 35 drums 4 and 5. In the use of the clam-shell bucket equipment of Fig. 1, where high speed and less power are the requirements, the high speed drive gearing will be placed in action for the operation of the drums 4 40 and 5 controlling the movement of the cables winding thereabout under the action of the friction clutches 28 and 29 that are operable from suitable levers in the lever assembly of the machine. The tag line shown in Fig. 1 45 winds about the tag line drum 31, shown best in Fig. 5, and also in Figs. 9 and 13.

By merely changing the cable and bucket equipments of Fig. 1, a drag-line bucket and cable equipment may be used in connection 50 with the machinery of Fig. 5, under which conditions the drum 4 becomes a drag drum as previously stated. In this type crane it is only necessary to shift the clutches for the drive gearing so as to put into action the 55 slow speed drive gear 18 in connection with the gearing transmitting motion therefrom to the drums 4 and 5, whereupon, the high speed gear 9 being inactive, the drums 4 and 5 will be operated at relatively slow speed 60 with increased power as necessary to meet the usual requirements of practice in drag-line work.

Thus far the drums 4 and 5, so far as their functions are concerned in the phases of converting the crane from a clam-shell to a

drag-line bucket crane, might be stated to be ordinary drums in their construction and operation. However, the drum 4 is made of a special construction and with special associated planetary drive gearing in order that 70 said drum may be operated in reverse directions to control the operation of a cable which is adapted to crowd out or project the dipper stick of a shovel, and rack in said stick as necessary for shovel operations. 75 In other words, while the driving of the drum in one direction is entirely sufficient for ordinary uses of this drum in hoisting, clam-shell, and drag-line work, the drum 4 must be convertible into a reversible combined crowding and racking in drum in order that it may perform the requirements of power shovel work. The means by which we accomplish the foregoing represent an 80 important feature of this invention. In 85 practical effect, it is by this means that we obtain highly important convertibility phases of operation of the main operating machinery of the crane.

Referring now to Figures 6 to 9^A inclusive, a preferred construction of the drum 4 will be described. This drum may be used with the interchangeable shovel boom equipment depicted in Figures 3 and 6, as comprising the boom 32 and the dipper stick 33. 90 A shipper shaft 34 carries the auxiliary reversing drum 35, see Figures 7 and 8, the ends of the shaft 34 carrying the shipper block castings 36 that swing free on the shaft. Each of the castings 36 has a journal 37 on its inner side resting in a bearing on the adjacent side member of the boom 32. Crowding pinions 38 are mounted between the sides or jaws of the casting 36 and keyed to the shipper shaft 34 so as to be operated thereby, and these pinions 38 engage with the racks 39 on the lower side of the dipper stick 33. Crowding and racking in cables 40 and 41 respectively, each having one end thereof secured to the drum 35, wind about 100 said drum in opposite directions and alternately wind on and off thereof during the turning of the drum. These cables 40 and 41 pass under fleeting sheaves 42 mounted near the base of the boom 32 and adjustable by suitable tension take up means designated 105 43. From the sheaves 42 the cables 40 and 41 pass upwards to the main operating drum 4 which when used with the shovel type equipment is a combined crowding and racking in drum. Said cables 40 and 41 are secured to wind about the drum 4 in opposite directions, so that when the drum 4 is turned 110 in one direction the cable 41 will be wound up and will turn the auxiliary reversing drum 35 on the boom 32, in a direction to rack in the boom owing to the driving action of the pinions 38. The opposite movement of the drum 4 will unwind therefrom 115 the cable 41, and wind thereon the cable 40, 120 125 130

which will compel a rotation of the drum 35 in a contra-clockwise direction, at reduced speed, as seen in Figure 6, effecting a crowding out of the dipper stick 33 in an obvious manner. The normal forward driving action of the drum 4 is preferably utilized for producing one of the movements of the dipper stick as above described, and the reverse operation is utilized to effect the crowding out movement. Said reverse operation is obtained by employing certain planetary gearing, best shown in Fig. 9, where the construction will be seen to comprise the outside band friction clutch 29 and driving gear 27 by which the drum 4 is adapted to be rotated in one direction for winding up one of the cable means by which the dipper stick is actuated. A winding of the other cable means to secure a reversing of the movement of the dipper stick is effected by certain planetary gearing now to be set forth. The planetary gearing includes a floating spider 44 mounted on the shaft 12 which carries the drum 4, said spider supporting the idler planetary gears 45 by means of the bearing pins 46. The idler gears 45 mesh with the inner or central driving gear 47 which is keyed to the shaft 12 so that it revolves with the gear 27 that is also keyed on said shaft, being driven from the engine in a manner heretofore fully explained. When it is desired to wind up the crowding cable 40 the drum 4 may be operated for this purpose by actuation of the planetary brake band 48 to engage it with the periphery of the spider 44, thereby holding said spider stationary. Under these conditions of course the gear 47 continuing to revolve with the shaft 12, rotates the idler gears 45 and transmits movement therefrom to the internal gear 49 which meshes therewith and is attached to the end of the drum 4 opposite that with which the friction clutch 29 co-acts. I utilize another friction brake band 50 engaging the end portion of the drum 4 equipped with the gear 49 for the purpose of holding the drum stationary when neither the friction clutch 29 nor planetary brake band 48 are in co-operation with the parts engaged thereby. Under these conditions, of course, the dipper stick 33 will also be maintained stationary.

Figures 10, 11, and 12 show that we may use sprocket chain driving means intermediate the drums 4 and 35, in substitution for the cable driving means which have thus far been described. In the said modification it is contemplated to detachably secure to the drum 4 a sectional sprocket wheel 51. A sprocket chain 52 may be engaged with said wheel 51 and extend over suitable transmitting sprockets at the base of the boom upwards to a special sprocket wheel 53 mounted on the shipper shaft 34 instead of the drum 35.

Again in Figures 13 to 16 inclusive, there is shown a further modification of the driving means for the drum 4 enabling it to be reversibly actuated for use in conjunction with shovel type boom apparatus. In the last noted construction the tag-line drum is designated at 31 and is operable through the use of planetary gearing and clutch devices for crowding out the dipper stick by winding on the drum the crowding cable 40. The planetary clutch is designated 54, the spider 55, the planetary idler gears 56, their bearing pins 57, and the inner planetary driving gear 58. The action of these parts is substantially like the planetary gearing previously referred to. The main operating drum 4 in this construction is utilized for winding up the racking in cable 41 and said drum 4 is provided with the special brake 55' to perform the function of the brake 50, namely, as a holding means for maintaining the dipper stick in a stationary position. The parts 27 and 29 in Figure 13, operate substantially as those parts have been explained hereinbefore.

In Figures 13 and 14 the internal gear is designated at 59 and is carried by the tag-line drum 31, of course. 60 denotes a winch-head which in one form or another is employed in the different constructions of our invention, for the usual purpose of a member of this sort.

It will be evident from the foregoing that the reversing operations of the main operating drum 4 are only utilized in the power shovel adaptation of our crane construction. When the crane is used for hoisting, clam-shell, and drag-line classes of work, the normal drive of the drum 4 in one direction is availed of, though of course the speed of the drum is varied in accordance with the demands of the work, as to whether speed is desired at the sacrifice of power, or power at the sacrifice of speed.

It is of course possible that under certain conditions of extension of the uses of crane for work of different kinds the adaptability of the drum 4 to be operated in reverse directions may be of special advantage other than has been specifically set forth herein. It will be evident, however, that the particular means utilized by us to transmit the reverse driving effects of the drum 4 to the dipper stick 33 may be considerably varied within the purview of the invention.

It is notable that the planetary gearing herein set forth not only enables a reversing action of the drum 4, but affords a gear reduction at the same time which is especially useful, if not necessary, for the efficient crowding out operation in the power shovel adaptation of the machine.

Having thus described our invention, what we claim as new and desire to secure by Letters Patent, is;

1. A crane comprising a body and interchangeable clam-shell, drag-line, and shovel cable and bucket apparatuses therefor, and operating mechanism adapted to operate 5 any one of said apparatuses, with different driving speeds for the clam-shell and drag-line apparatuses.
2. A crane comprising a body, interchangeable boom and bucket apparatuses 10 for clam-shell and power shovel work, and operating means on the body for actuating at different speeds either type of such apparatuses when placed in position on the body.
3. A crane comprising a body, interchangeable boom and bucket apparatus for drag-line and power shovel work, and variable speed means on the body for actuating either type of such apparatuses when placed 15 in position on the body.
4. A crane comprising a car, and operating machinery thereon including hoisting and main operating drums, and means to drive said drums at variable speeds for the operation of clam-shell or drag-line bucket 20 equipment, and for driving one of the drums reversibly for the operation of power shovel equipment.
5. A crane comprising operating machinery including operating drums for actuation of clam-shell, drag-line, and shovel 25 types of bucket equipments, and means to changeably actuate the drums to enable them to properly actuate any one of the above types of bucket equipment.
6. In combination, a crane comprising hoisting and main operating drums, boom equipment including interchangeable cable and bucket devices of the clam-shell and drag-line types, other boom equipment including power shovel, cable, dipper arm, and dipper devices usable in substitution for the first named boom equipment, and means to control said drums to cause proper operation of said boom equipments, whichever 40 may be desired to be employed, at different speeds.
7. In combination, a crane comprising hoisting and main operating drums, boom equipment including interchangeable cable and bucket devices of the clam-shell and drag-line types, other boom equipment including power shovel, cable, dipper arm, and dipper devices usable in substitution for the first named boom equipment, and means to control said drums to cause proper operation of said boom equipments, whichever 45 may be desired to be employed, comprising variable speed means for the drums for their actuation when either the clam-shell or drag-line means is used, and reversible mechanism for driving one of the drums for employment when the shovel type of means is availed of.
8. In a crane, the combination of hoisting 50 and operating drums, change speed means for driving them at high and low speeds, means to drive one of the drums in a reversible manner, and different cable and bucket equipments interchangeably co-operative with the drums, and with either the change speed and reversible means for the drums, dependent upon which of the said equipments is availed of.
9. In a crane, the combination of hoisting and operating drums, change speed means for driving them at high and low speeds, means to drive one of the drums in a reversible manner, and different cable and bucket equipments interchangeably co-operative with the drums, and with either 70 or both the change speed and reversible means for the drums, dependent upon which of the said equipments is availed of.
10. In a crane of the class described, the combination of a body, boom and bucket mechanisms of different types adapted to be connected thereto, operating machinery on the body comprising a motor, main hoisting and operating drums, change speed gearing connecting said motor with said drums for operating the latter at different speeds according to the particular type of boom and bucket mechanism associated therewith, and means whereby one of the drums may be reversibly operated according to a certain class of boom and bucket mechanism that may be connected up for operation under the control of the said drums.
11. In a crane of the class described, the combination of the body, boom and bucket mechanisms of different types adapted to be connected thereto, operating machinery on the body comprising a motor, main hoisting and operating drums, change speed gearing connecting said motor with said drums for operating the latter at different speeds according to the particular type of boom and bucket mechanism associated therewith, and means whereby one of the drums may be reversibly operated according to a certain class of boom and bucket mechanism that may be connected up for operation under the control of the said drums, the last mentioned means including planetary gearing 100 co-operative with one of the drums to reverse its movement.
12. A crane comprising a car, and operating machinery thereon including hoisting and main operating drums, and means to drive said drums at variable speeds for the operation of clam-shell or drag-line bucket equipment, and for driving one of the drums reversibly at different speeds for the operation of power shovel equipment.
13. In combination, a crane comprising hoisting and main operating drums, boom equipment including interchangeable cable and bucket devices of the clam-shell and drag-line types, other boom equipment including power shovel, cable, dipper arm, 120
- 65

- and dipper devices usable in substitution for the first named boom equipment, and means to control said drums to cause proper operation of said boom equipments, which ever may be desired to be employed, comprising variable speed means for the drums for their actuation when either the clam-shell or drag-line means is used, and planetary gearing driven by said speed means and affording reversing and speed reduction means for employment when the shovel type boom equipment is used.
14. In a crane, the combination of hoisting and operating drums, change speed means for driving them at high and low speeds, means to drive one of the drums in a reversible manner, and with a change of speed different from those above mentioned, and different cable and bucket equipments interchangeably co-operative with the drums, and with either or both the change speed and reversible means for the drums, dependent upon which of the said equipments is availed of.
15. In combination, a crane comprising a car, and operating machinery thereon for operation of different types of boom and bucket equipments, comprising a main operating drum for cable means adapted to operate an excavating bucket, and a driving member on said drum for operating the shipper shaft by which a dipper stick of a shovel may be racked in or crowded out, means detachably securing the said driving member to the drum enabling its removal when the drum is to operate the cable of an excavating bucket instead of said dipper stick, and means for operating the drum in reverse directions.
16. In combination, a crane comprising a car, and operating machinery thereon for operation of different types of boom and bucket equipments, comprising a main operating drum for cable means adapted to operate an excavating bucket, and a driving member on said drum for operating the shipper shaft by which a dipper stick of a shovel may be racked in or crowded out, means detachably securing the said driving member to the drum enabling its removal when the drum is to operate the cable of an excavating bucket instead of said dipper stick, and means for operating the drum in reverse directions at a high speed when the detachable driving member is used and is causing racking in of the dipper stick, and at reduced speed when said driving member is crowding out the dipper stick.
17. In combination, a crane comprising a car, and operating machinery thereon for operation of different types of boom and bucket equipments, comprising a main hoisting drum and a main operating drum, the latter adapted for cooperation to drive different kinds of boom, and bucket equipments includ-
- ing clam-shell, drag-line, and shovel types, special means to effect reverse operations of the operating drum, a driving member on the said operating drum, a shovel boom and bucket equipment including a dipper stick and shipper mechanism for racking in and crowding out said stick, means connecting the shipper mechanism and said driving member for actuating the dipper stick, and means to detach the driving member from its drum so an operating cable of clam-shell or drag-line excavating buckets may be directly connected therewith and operated thereby.
18. In combination, a crane comprising a car, and operating machinery thereon for operation of different types of boom and bucket equipments, comprising a main hoisting drum and a main operating drum, the latter adapted for cooperation to drive different kinds of boom and bucket equipments including clam-shell, drag-line, and shovel types, special means to effect reverse operations of the operating drum, at different speeds, a driving member on the said operating drum, a shovel boom and bucket equipment including a dipper stick and shipper mechanism for racking in and crowding out said stick, means for actuating the dipper stick, and means to detach the driving member from its drum so an operating cable of clam-shell or drag-line excavating buckets may be directly connected therewith and operated thereby.
19. In combination, a crane comprising a car, and operating machinery thereon for operation of different types of boom and bucket equipments, comprising a main hoisting drum and a main operating drum, operable at different speeds to produce the highest efficient speed operations, interchangeably, of clam-shell and drag-line bucket equipments, the latter adapted for co-operation to drive different kinds of boom and bucket equipments including clam-shell, drag-line, and shovel types, special means to effect reverse operations of the operating drum, a driving member on the said operating drum, a shovel boom and bucket equipment including a dipper stick and shipper mechanism for racking in and crowding out said stick, means connecting the shipper mechanism and said driving member for actuating the dipper stick, and means to detach the driving member from its drum so an operating cable of clam-shell or drag-line excavating buckets may be directly connected therewith and operated thereby.
20. In combination, a crane comprising a car, and operating machinery thereon for operation of different types of boom and bucket equipments, comprising a main hoisting drum and a main operating drum, the latter adapted for co-operation to drive dif-

ferent kinds of boom and bucket equipments including clam-shell, drag-line, and shovel types, special means to effect reverse operations of the operating drum, means to operate the operating drum at desired speed for clam-shell and drag-line work, means enabling reverse motion of the operating drum for dipper shovel work to operate the shipper mechanism of a dipper stick, and said 10 operating drum being constructed to receive driving equipment for the actuation of either clam-shell or drag-line, and dipper shovel equipment.

21. In combination, a crane comprising a 15 car, and operating machinery thereon for operation of different types of boom and bucket equipments, comprising a main hoisting drum and a main operating drum, the latter adapted for co-operation to drive

different kinds of boom and bucket equipments including clam-shell, drag-line, and shovel types, special means to effect reverse operations of the operating drum, means to operate the operating drum at different speeds, high speed for clam-shell work and 20 low speed for drag-line work, means enabling reverse motion of the operating drum at different speeds for dipper shovel work to operate the shipper mechanism of a dipper stick, and said operating drum being constructed to receive driving equipment for the actuation of either clam-shell or drag-line, and dipper shovel equipment.

In testimony whereof we affix our signatures.

ALPHEUS E. HOLCOMB.
LESLIE A. RUSSELL.
